UNITED STATES PATENT OFFICE.

HARRY H. VICKERS, OF CORONA, LONG ISLAND, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed March 15, 1922. Serial No. 543,971.

To all whom it may concern:

Be it known that I, HARRY H. VICKERS, a citizen of the United States, residing in Corona, Long Island, in the county of 5 Queens and State of New York, have invented certain new and useful Improvements in Typewriting Machines, of which the following is a specification.

This invention relates to typewriting 10 machines, and more particularly to means for rapidly inserting cards and worksheets around the platen, and also for collating and positioning the same thereon.

In the embodiment of the invention here- 15 disclosed, provision is made of a rapid inserting device, of which the inserter handle is preferably mounted to turn about the axis of the platen-shaft and is provided with a tooth which is normally out of en- 20 gagement with the usual toothed wheel on the platen-shaft. Upon depression of the inserter handle against the action of a spring, the tooth thereon may be brought into engagement with said toothed wheel and, upon swinging the inserter handle rearwardly, a work-sheet or card brought 25 into engagement with the usual feed-rolls at the point where the latter contact with the platen will be drawn between the feed- 30 rolls and platen and carried around to the front of the latter.

During the rotation of the handle of the inserter or platen sweep, the tooth is held 35 in engagement with the toothed wheel by means of a stud on the handle which engages the inner edge of a ring on a stationary disk, and, when the inserter handle is arrested in its rear position, the connection between the inserter and the platen-shaft 40 is automatically broken as a result of the provision in the ring of a notch into which the stud snaps, and the tooth is withdrawn from the toothed wheel. Provision is also made of a notch in the ring at the forward 45 limit of the movement of the handle so that the platen will be released from the handle and may be line-spaced by the usual line-space handle or by the usual finger-wheels.

According to one method of using the in- 50 vention, a wide record-sheet is inserted around the platen and two cards are collated side by side and between the record-sheet and the platen. The record-sheet is first inserted and adjusted to typing posi-

tion by means of the usual line-space lever 55 or finger-wheels at the ends of the platen-shaft. In order to insert the cards and collate the same properly with reference to the record-sheet, the record-sheet must be shifted rearwardly by pulling the inserter 60 handle forwardly to its stop. The cards are then inserted behind the platen or collated between the platen and the record-sheet.

In order to insure proper positioning or collating of the cards with reference to the 65 record-sheet, and also to prevent slipping of the cards with reference to the record-sheet as the latter is carried forward by the platen to the proper position for typing, provision is made of suitable means to gage 70 the cards at the rear of the platen and to assist in carrying the leading ends of the cards between the rear feed-rolls and the platen as the record-sheet is advanced by 75 the platen when the latter is actuated by the inserter handle. To this end, provision may be made of a collating plate forming part of a bail, the two arms of which are pivoted to the ends of the platen-frame near the front thereof, so that, when the 80 bail is swung down to the rear, the collating plate thereof will extend across the rear paper-table and be positioned above the same.

The cross-bar may be in the form of a 85 plate having turned-over portions at its upper edge to serve as end gages for truing up and gaging the cards, and provision may be made of side-edge gages preferably adjustable on said plate. The plate may 90 also be cut away at certain places in its upper edge so that the upper edges of the cards may be grasped conveniently while gaging the same against the end gages referred to. The plate may also be provided along its lower edge with fingers to assist in supporting the cards. Preferably, the bail is held in slightly raised position by spring means, so as to enable a card, of the size to be used, to be placed against the 95 rear feed-rolls and its upper edge inserted beneath the corresponding top gage on the collating plate or cross-bar of the bail. After the card or cards have thus been positioned and also set against the side gages, 100 the bail may be pressed downwardly to tend to thrust the cards between the platen and the feed-roll at the same time that the in-

serter handle is operated to rotate the platen and advance all of the collated work-sheets or pieces. In this manner, relative slipping between the record-sheet and the cards will be prevented, and the cards will be properly positioned with reference to the record-sheet when advanced accurately to the writing line by the mechanically-measured stroke of the inserter or platen-sweep.

10 Provision may also be made of suitable stopping means to prevent the bail from being depressed to too great an extent in inserting the cards, and provision may also be made of suitable means on the bail and 15 the carriage whereby the bail may be supported when swung forwardly.

Obviously, the card-inserting device may also be used occasionally to insert cards when no record-sheet is to be used. Single 20 cards may be used, or superposed cards with carbons interleaved between the same. In order to obtain a carbon copy on the card when a record-sheet is used, preferably a carbon-sheet of the same size as the card 25 is attached thereto by any suitable means or placed loosely thereon and both set against the top and side gages on the collating plate.

Other features and advantages will hereinafter appear.

30 In the accompanying drawings,

Figure 1 is a diagrammatic view, looking down from above, of a portion of a platen-frame of an Underwood standard typewriting machine with my invention applied 35 thereto.

Figure 2 is a front view of the structure shown in Figure 1.

Figure 3 is a sectional front view of the 40 inserting device shown at the right in Figure 2.

Figure 4 is a view, looking from the right, of the structure shown in Figure 1, parts being broken away to show the underlying structure.

45 Figure 5 is a diagrammatic view similar to Figure 4, but with the inserter handle in its forward limiting position preparatory to inserting a record-sheet.

Figure 6 is a view similar to Figure 5, 50 showing the record-sheet inserted.

Figure 7 is a view similar to Figure 6, but showing the inserter handle thrown to the front, the record-sheet being in its rearward position, and a card positioned between the rear feed-rolls and the end gage 55 of the card-inserting bail.

Figure 8 is a view similar to Figure 7, showing the card and record-sheet advanced to the position for typing.

60 Figure 9 shows the bail supported in its forward position.

A cylindrical platen 11 comprises ends 12, which are secured by means of set-screws 13 on a platen-axle 14 journaled in 65 left and right hand ends 15 and 15^a, re-

spectively, of a platen-frame 16. Mounted on the left-hand end of the platen-axle 14 is a usual line-space wheel 17 and a finger-wheel 18, and provision is made of a usual line-space lever 19 to actuate, through a slide 20 and other parts, not shown, the line-space wheel 17.

Provision is made at the right-hand end of the platen-frame of rapid-inserting means, comprising a handle 21 mounted on a bar or arm 22 having pin-and-slot connections with a crank 23 mounted to swing about the axis of the platen-axle 14. The bar 22 is provided with a tooth 24 extending through an opening 25 in the crank 23, so that it may be depressed into engagement with teeth 26 of a gear 27 fixed on a rotatable stub-shaft or member 28, which is provided at its inner end with an opening 29 into which the right-hand end of the platen-axle 14 extends and is secured by means of set-screws 30. For convenience, a spacing sleeve 31 may be positioned on the platen-axle 14 between the rotatable member 28 and the boss 32 mounted on the end 15^a of the platen-frame and through which the platen-axle passes.

To furnish proper support for the rotatable member 28, provision is made of a bracket 33 supported on the end 15^a of the platen-frame and provided with a downwardly-extending portion or flange 34 having an opening into which a reduced portion 35 of the rotatable member 28 projects. The main portion of the bracket 33 is substantially horizontal and extends over the top of a flange 36 at the upper edge of the platen-frame end 15^a. In order to give a suitable support for the bracket 33, a tongue 37 is cut out of the same and turned downward at right angles to the main portion of the bracket, and, to furnish a suitable abutment against which the tongue 37 may rest, use is made of the usual cover-plate 38, placed with one of its flanges 39 lying on the flange 36, and the other flange 40 extending downwardly in contact with the tongue 37.

As seen in Figure 3, the flange 39 extends to the left slightly beyond the left-hand edge 41 of the opening formed in cutting out the tongue 37, the horizontal portion of the bracket 33 therefore serving to maintain the flange 39 in horizontal position. Above the flange 36 and over the corresponding portion of the bracket 33 extends a horizontal flange 42 of an angle bracket 43 having a vertical flange 44 for a purpose to be described hereinafter. Screws 45 extend through said flange 42 and secure the same as well as the bracket 33 to the flange 36 of the platen-frame end 15^a.

The rotatable member 28 is positioned on the platen-axle by inserting its reduced portion through the corresponding opening in

the flange 34 of the bracket 33 until a flange or collar 46 thereon engages the outer face of the flange 34, the set-screws 30 then being tightened to hold the rotatable member 28 5 on the platen-axle 14. Immediately to the right of the collar 46 is a stationary grooved cam disk 47, which fits over the main portion of member 28 and has a circular slot or groove 48 into which extends, 10 and by which is controlled, a stud 49 projecting rigidly from the bar 22 on the side opposite the tooth 24. The stud 49, when in engagement with the outer wall of the groove 48, is held so as to maintain the bar 22 in depressed position with the driving tooth 24 in engagement with the teeth 26 of the gear 27. When, however, the handle is moved to the rear position as shown in Figure 4, or to the forward position as shown 15 in Figure 5, the stud 49 will be released so as to permit the bar 22 to be moved away from the axis of the platen-axle to withdraw the tooth 24 from engagement with the teeth 26. This result is obtained by 20 providing notches 50 and 51 in the outer portion 52 of the disk 47, these notches being formed in the outer side of the groove 48, and by providing a spring 53 held by a pin 54 in a notch 54^a in the disk 47 at the 25 inner side of the groove 48, and having arms 55 and 56 over one of which the stud 49 must pass when the handle 21 moves to one of its extreme positions. The disk 47 is held against rotation by means of suitable pins 57 and 57^a extending therefrom and connected with the flange 34 of the bracket 33. The pin 57^a extends beyond the outside face of the disk 47 and serves as a stop to limit the rearward movement of the handle 30 21, and a stop 57^b serves to limit the forward movement.

The crank 23 is provided at one end with a hub 58 encircling the rotatable member 28 and spaced from the disk 47 by means 45 of a collar 59. Just to the right of the hub 58, as seen in Figure 3, is positioned the gear or toothed wheel 27 which is mounted on a reduced portion 60 of the rotatable member 28 and secured thereto by suitable 50 means, such as a pin 61, and a finger-wheel 62 of the usual form is secured on a still smaller portion 63 of the rotatable member 28 by means of a set-screw 64. Preferably, the connection between the crank 22 and the bar 23 is effected by means of shoulder-screws 65 extending through slots 66 in the bar 22 and threaded into the crank 23.

Provision is made of a rear paper-table 67 and rear and front feed-rolls 68 and 69, 55 respectively. When it is desired to introduce a record-sheet 70, the latter is introduced over the rear paper-table 67 until its leading edge engages the rear feed-rolls 68 and the platen 11, the handle 21 being in its forward position as shown in Figure 5.

Upon pressing the handle 21 towards the axis of the rotatable member 28, the tooth 24 will engage between two of the teeth 26 of the gear 27, and the platen may then be rotated until the handle assumes the position shown in Figure 6, the tooth 24 being maintained in engagement with the gear 27 during this movement by engagement of the stud 49 with the ring or guide 52. When the handle 21 reaches its rearward position, the spring arm 55 will shift the bar 22 to break the connection between the tooth 24 and the gear 27, and the platen may then be rotated to the desired position by means of the line-space lever 19 or either of the finger-wheels 18 and 62. The handle 21 is then swung forward again and the record-sheet brought to the position shown in Figure 7, preparatory to inserting a card 71 having a carbon-sheet 72 attached to the outer face thereof by any suitable means.

If the handle 21 were swung rearwardly with the card 71 merely placed in position between the record-sheet 70 and the platen 11, slipping might occur between the card 71 and the record-sheet 70. In order to avoid such slipping and to insure proper positioning of the card 71 with reference to the record-sheet 70, provision is made of a suitable card gaging or inserting device 95 which may be in the form of a bail 73, of which the right-hand arm 74 may be pivoted on the upright flange 44 by any suitable means, such as a screw 75, and the left-hand arm 76 may be pivoted by means of a screw 77 on the vertical flange 78 of a bracket 79 having a horizontal flange 80 resting on the flange 81 at the upper edge of the left-hand end 15 of the platen-frame, the flange 80 being secured in position by any suitable means, such as screws 82.

The cross-bar 83 of the bail is provided with turned-over portions 84 which serve as end gages for the cards 71 inserted at the rear of the platen. Preferably, two cards 110 71 are used at the same time, and these are positioned as shown in Figure 2, the left-hand edge of the left-hand card being gaged by a side gage 85, and the right-hand edge of the right-hand card 71 being gaged by a side gage 86. Each of the side gages 85 and 86 is provided with a slot 87 through which extend screws 88 by which the gages may be secured in position when properly adjusted. In order that the upper edges of the cards may be grasped conveniently in positioning the same against the end and side gages, provision is made of a central cut-out 89 and left and right end cut-outs 90 and 91, respectively. The cross-bar 83 is also provided with downwardly-extending fingers 92 to assist in guiding the cards.

In order to facilitate the insertion of cards 71 between the turned-over portions or end gages 84 and the rear feed-rolls 68, provision 120

is made by means whereby the bail 73 is normally held a short distance above its lower extreme position. To this end, brackets 93 and 94 are secured to the inner sides 5 of the arms 76 and 74, respectively. The bracket 93 is provided with a lug 95 projecting inwardly from the arm 76 and having on its lower face a cup 96 in which is secured the upper end of a helical spring 97 which normally rests on the flange 80 of the bracket 79. Similarly the bracket 94 is provided with an inwardly-extending lug 98 provided on its lower face with a cup 99 in which is secured the upper end 10 of a helical spring 100. As seen in Figure 2, the spring 100 lies to the left of the plane of the end 15^a, and, to furnish an abutment against which the lower end of the spring 100 may engage, a plate 101 is secured to 15 the lower face of the flange 42 of the bracket 43. This plate 101 extends into the opening of the bracket 33 formed by turning down the tongue 37.

It is also desirable to regulate the extent 20 of the downward movement of the bail 73, and, for this purpose, provision is made of brackets 102 and 103, respectively, secured to the cross-bar 83 at its left and right ends, respectively, these brackets being provided 25 with lugs 104 and 105, respectively, extending forwardly from cross-bar 83 and having threaded therein adjustable stops or screws 106 and 107, respectively. The screws 106 and 107 are so positioned as to engage respectively the flange 80 of the bracket 79 at the left end of the platen-frame and the plate 101 at the right end of the platen-frame. The bracket 102 is provided with 30 an upward extension 108, which, when the bail is thrown forwardly as shown in Figure 9, engages a guard 109 which is provided in some machines to extend over the line-space lever 19, the bail at its right-hand end resting on the usual finger 110 which extends upwardly on the right-hand end of the front bar 111 of the typewriter-carriage.

In practice, the mechanism may be used 35 in the following manner: A record-sheet 70 is introduced over the rear paper-table 67 and its forward or leading edge is brought into contact with the feed-rolls 68 as shown in Figure 5. The handle 21 may then be swung to the position shown in Figure 6, thus advancing the record-sheet 40 70 around the platen. When the handle 21 reaches this position, the tooth 24 is withdrawn from the gear 27, as hereinbefore described, and the platen 11 is free to be shifted by one of the finger-wheels 18 and 45 62 or by the line-space lever 19 to bring the record-sheet 70 into position to begin typing. The handle 21 is again connected with the gear or wheel 27 and swung to its forward position, feeding the record-sheet 50 70 rearwardly to the position shown in

Figure 7. A card 71 is then inserted in front of the cross-bar 83 and its leading edge carried down into engagement with the rear feed-rolls 68, the upper end of the card 71 being placed under one of the turned-over 55 portions or end gages 84, the springs 97 and 100 holding the bail in such a position as to facilitate the insertion of the card 71 under the corresponding end gage 84. The card 71 is also brought into engagement with one of the side gages 85 or 86. If two cards are used, another card 71 may also be placed in position under the other end gage 84. Upon depressing the bail 73, the card 71 will be urged to advance between the platen 11 and the rear feed-rolls 68, and, upon movement 60 of the handle 21 to advance the platen from the position shown in Figure 7 to that shown in Figure 8, the card 71 and the record-sheet will be advanced to typing position with the 65 card in proper adjusted position with reference to the record-sheet. Preferably, only one line of writing is to be typed on each card 71, and, when this typing has been completed, the platen is turned rearwardly 70 to the position shown in Figure 9, thus thrusting the cards 71 back over the rear paper-table 67. To facilitate the removal of the cards 71 from the rear paper-table 67, the bail 73 may be swung to its forward 75 position as shown in Figure 9. After the cards have been removed, the bail 73 may be swung to the rear again and other cards inserted. Before inserting a new set of cards, however, the platen 11 may be rotated 80 by means of the line-space lever 19 to bring the record-sheet 70 to the next printing line.

It may be noted, among other things, that the collating device is at the intake side of the platen, and comprises the shelf 67 extending upwardly in rear of the platen, and receiving the condensed record-sheet 70, which is inserted between the feed-roll 68 and the platen, and that the collating device also comprises the collating plate 83 85 arranged on edge intermediate said shelf and the platen, and that the cards or work-pieces 71 with their carbons 72 are adjusted on said intermediate collating plate 83 with reference to the condensed record-sheet 70 90 which is upon said paper-shelf 67, so that, when successive cards 71 are introduced and withdrawn, the corresponding typed impressions will follow one another properly on said condensed record-sheet, which 95 remains in the machine. It may also be noted that the intermediate plate 83 has at its top edge a gage 84 against which the card or work-piece 71 and the carbon 72 are trued up when they are presented in 100 inverted condition (Figure 7), between the platen and the condensed record-sheet. The plate 83 is movable toward the platen to thrust the carbon 72 with the work-piece 71 105 thereon between the feed-roll 68 and the 110

platens, and start them forwardly to typing position. Prior to this thrusting movement, the lower edge of the card is confined edge-wise between the bight of the platen and 5 the feed-roll 68, which therefore serves as a gage. In other words, the card (Figure 7) is closely confined between said feed-roll (or gage) and the gage 84 at the top of the collating plate 83. This is the final gaging 10 of the collated work-pieces; and from this finally gaged position the platen-sweep, by means of its mechanically-measured stroke, brings said gaged collated work-pieces a pre-determined distance to exact typing position. 15

Variations may be resorted to within the scope of the invention, and portions of the improvements may be used without others.

Having thus described my invention, I 20 claim:

1. In a front-strike typewriting machine, the combination with a revoluble platen and a feed-roll, of a work-collating device, comprising a shelf extending upwardly in rear 25 of the platen and receiving a condensed record-sheet inserted between the feed-roll and platen, and also comprising a collating plate on edge intermediate said shelf and the platen upon which is adjusted a card 30 or work-piece with a carbon therefor, said intermediate plate having at its top edge a gage against which the work-piece and carbon are trued up when presented in inverted condition between the platen and 35 the condensed record-sheet, said plate being mounted to be swung forwardly clear of the platen to give access to the typed and returned card for removing the same from the machine.

2. An attachment for a typewriting machine, comprising a bail having arms to be pivoted on the ends of the platen-frame over the front side of the platen to swing at the intake side, and a flat cross-bar connecting 45 said arms, an end gage forming part of said cross-bar and perpendicular thereto at its upper edge to gage the upper end of a card to be inserted at the rear of the platen, and a side gage adjustably mounted on the 50 cross-bar to engage a side edge of said card.

3. An attachment for a typewriting machine, comprising a bail having arms to be pivoted on the ends of the platen-frame 55 over the front side of the platen to swing at the intake side, and a flat cross-bar connecting said arms, an end gage forming part of said cross-bar and perpendicular thereto at its upper edge to gage the upper end 60 of a card to be inserted at the rear of the platen, a side gage adjustably mounted on the cross-bar to engage a side edge of said card, said cross-bar, being cut away at its upper edge to permit the card to be grasped 65 at its upper edge while being placed in

gaged position, and card-controlling fingers extending from said cross-bar at its lower edge, to guide and control the card during insertion and removal of same from the machine. 70

4. An attachment for a typewriting machine, comprising a bail having arms to be pivoted on the ends of the platen-frame over the front side of the platen to swing at the intake side, and to swing said bail in front 75 of the platen to give unobstructed access at the intake side, and a flat cross-bar connecting said arms, an end gage on said cross-bar and perpendicular thereto at its upper edge to gage the upper end of a card to be inserted around the platen, and a side gage for said card adjustable on said bar longitudinally thereof. 80

5. An attachment for a typewriting machine, comprising a bail having arms to be pivoted on the ends of the platen-frame over the front side of the platen to swing at the intake side, and a flat cross-bar connecting 85 said arms, an end gage on said cross-bar and perpendicular thereto at its upper edge to gage the upper end of a card to be inserted around the platen, a side gage for said card adjustable on said bar longitudinally thereof, and card-controlling fingers extending from the bar and forming part 90 thereof at its lower edge. 95

6. An attachment for a typewriting machine, comprising a bail having arms to be pivoted on the ends of the platen-frame over the front side of the platen to swing at the intake side, and a flat cross-bar having two 100 end gages perpendicular thereto at its upper edge and symmetrically positioned on opposite sides of the middle of said cross-bar, said cross-bar being cut out between 105 said end gages to permit cards gaged by the latter to be grasped at their upper ends.

7. An attachment for a typewriting machine, comprising a bail having arms to be pivoted on the ends of the platen-frame over 110 the front side of the platen to swing at the intake side, and a flat cross-bar having two end gages perpendicular thereto at its upper edge and symmetrically positioned on opposite sides of the middle of said cross-bar, said cross-bar being cut out between 115 said end gages and also adjacent the outer end of each of said end gages to permit cards gaged by the latter to be grasped at their upper ends. 120

8. An attachment for a typewriting machine, comprising a bail having arms to be pivoted on the ends of the platen-frame over the front side of the platen to swing at the intake side, and a flat cross-bar having two 125 end gages perpendicular thereto at its upper edge and symmetrically positioned on opposite sides of the middle of said cross-bar, said cross-bar being cut out between said end gages to permit cards gaged by the 130

6
latter to be grasped at their upper ends, and a side gage on said cross-bar adjacent the outer end of each of said end gages.

9. A rapid inserting device for a type-writing machine comprising a toothed wheel to be connected with the platen-axle to rotate the same, a handle comprising an arm to rotate about the axis of said wheel, a second arm slidable longitudinally of the 10 first-mentioned arm, a tooth projecting from the second-mentioned arm through a slot in the first-mentioned arm to engage said wheel, a follower projecting from the second-mentioned arm on the opposite side 15 of the tooth, a ring to engage said follower and thereby hold said tooth in engagement with said wheel when the handle is operated, said ring having notches corresponding to the limiting positions of the handle so as 20 to release the follower when the handle reaches either of said limiting positions, and a spring to urge outwardly the arm carrying the follower.

10. In combination, a platen, a platen- 25 axle, a platen-frame having ends in which

said axle is journaled, one of the ends of the platen-frame having a flange extending at right angles thereto at its upper edge and a cover-plate comprising a portion lying along the flange at the top of the platen frame end and a flange extending vertically downward therefrom, a bracket for a rapid inserting device, said bracket comprising a plate having one end resting on the upper flange of the cover-plate and having a 30 tongue cut out thereof and bent downwardly to lie in engagement with the outside face of the downwardly-extending flange of the cover-plate, said bracket having a downwardly-extending flange with 35 an opening coaxial with the axis of the platen, a rotatable member journaled in the opening of the downwardly-extending flange of the bracket, means to connect the rotatable member with the platen-axle so as to rotate therewith, and means on the outside of the flange of the bracket to rapidly rotate said rotatable member and therefore said platen. 40 45

HARRY H. VICKERS.
